(57) **CLAIM**

The ornamental design for a notebook computer with liftable display, as shown and described.

DESCRIPTION

FIG. 1 is a perspective view of a notebook computer with liftable display showing our new design in a partially opened state of use;

FIG. 2 is another perspective view;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in another partially opened state of use;

FIG. 10 is left side view thereof;

FIG. 11 is a perspective view thereof in another partially opened state of use;

FIG. 12 is another perspective view thereof; and,

FIG. 13 is a perspective view thereof in a closed state of use. The dashed broken lines illustrate portions of the notebook computer with liftable display and form no part of the claimed design.
